(57) **CLAIM**

The ornamental design for a foot platform for exercise apparatus, as shown and described herein.

DESCRIPTION

FIG. 1 is a top perspective view of a foot platform for exercise apparatus, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the figures are for the purpose of illustrating portions of the foot platform for exercise apparatus, which form no part of the claimed design.

1 Claim, 7 Drawing Sheets
